CAMPING KIT

George Walters, New York, N. Y.

Application November 9, 1943, Serial No. 509,545

4 Claims. (Cl. 292—194)

This invention relates to new and useful improvements in a camping kit.

The present application is a refile of my abandoned application filed on April 21, 1941, Serial No. 389,552.

More specifically, the invention proposes the construction of a camping kit characterized by a box-shaped body having a plurality of partitions dividing off compartments therein and a cover for closing said body in a manner to isolate each of the compartments.

Still further it is proposed to characterize the cover by a top compartment having a downwardly extending skirt wall portion provided with a novel means arranged in a manner to retain the cover in position upon the boxlike body.

Still further it is proposed to provide the skirt wall portions of the cover with pivotally mounted flaps engageable with complementary latches mounted on opposite sides of the body to hold the cover in position.

A further object of the invention is the provision of openings in the flaps engageable with spring pressed complementary members mounted on the body for securing the flaps in position and arranged in a manner so that a nail or similar object may be passed through the openings in one of the flaps for supporting the cover in a position to expose a mirror mounted on the inside face thereof.

A further object of this invention proposes the provision of a means for permitting the cover to be fixedly locked in position of the boxlike container with its top wall spaced from the open top of the container to varying degrees to permit articles to be positioned within this space.

For further comprehension of the invention, and of the objects and advantages thereof, reference will be had to the following description and accompanying drawing, and to the invention as more particularly set forth.

In the accompanying drawing forming a material part of this disclosure:

Fig. 1 is a perspective view of a camping kit constructed in accordance with this invention.

Fig. 2 is a perspective view of the cover, per se.

Fig. 3 is a perspective view of the box shaped body with the cover removed.

Fig. 4 is a perspective view similar to a portion of Fig. 1 but illustrating a modification of the invention.

Fig. 5 is a vertical sectional view taken through one of the flaps.

Fig. 6 is a view similar to Fig. 5 but illustrating the position of the parts in the released condition of the latching means.

Fig. 7 is a horizontal sectional view taken on the line 7—7 of Fig. 6.

The camping kit, according to this invention, comprises a box shaped body 10 having a plu-

rality of partitions 11 mounted therein for dividing the interior of the box shaped body into a plurality of separate compartments into which toilet articles may be positioned. The box shaped body 10, as well as the partitions 11 are preferably constructed of metal.

A cover 12 is provided for closing the open top of the box shaped body 10. The cover 12 comprises a top wall 13 and a depending skirt wall portion 14. This cover 12 is also constructed of metal and is provided with a mirror 15 on the inside of its top wall portion 13.

Flaps 16 are pivotally mounted upon opposite sides of the cover 12. These flaps 16 are preferably pivotally mounted on the bottom edges of the depending skirt wall portions 14 of the cover. Each of the flaps 16 is provided with a right angular foot portion 17 which is engageable beneath the bottom wall of the box shaped body 10 for holding the cover in position thereon. Latches 18 are mounted on opposite sides of the box shaped body 10 and are engageable with the flaps 16 for holding the flaps against pivoting into a position in which the footlike portions 17 would be disengaged from beneath the box shaped body 10. Each of the latches is characterized by a metal plate 19 riveted to the side of the boxlike body 10 and provided with a projecting resilient stud 20 which is engageable with a complementary opening 21 formed in the flap 16.

The operation of this form of the invention is as follows:

The cover 12 is placed on the box shaped body 10 and the flaps 16 are pivoted to cause their footlike extensions 17 to engage beneath the bottom wall of the box shaped body 10. This movement of the flaps causes the projecting studs 20 to be engaged through the openings 21 for holding the flaps 16 in their operative positions. For removing the cover it is merely necessary to manually pivot the flaps to disengage the studs 20 from the openings 21.

When the cover 12 is removed from the box shaped body 10 it may be hung on a vertical wall by passing a nail or similar object through one of the openings 21 with the inside face of the top wall portion 13 exposed to permit one to use the mirror 15.

According to the modification of the invention shown in Figs. 4 to 7 the construction of the camping kit is similar to that previously described and is characterized by a box shaped body 10 closed by means of a cover 12' having a top wall portion 13' and a deep depending skirt wall portion 14'.

Flaps 15' are pivotally mounted on the bottom edges of the depending skirt wall portions 14' and each is provided with an extendable bottom section 25. Each of the flaps 15' further has a top section 26 which is pivotally attached to the

bottom edge of the skirt wall portion 14'. The bottom end of the top section 26 is slidably extended into a hollow 27 projected inwards from the top of the bottom section 25. A latch is mounted on the body 10' and is characterized by a projecting resilient stud 20 engageable with a complementary opening 21' formed in the bottom section 25 for holding the flap 15' in a position in which the cover 12' will be in a position upon the box shaped body 10'.

A means is provided for latching the extendable bottom section 25 of the flap 15' in various extended positions relative to the top section 26 for holding the cover 12' in a position in which its top wall portion 13 will be supported to varying degrees above the open top of the box shaped body to provide an auxiliary space within which a towel or similar object may be carried.

This means is characterized by a pivotally mounted lever 28 mounted upon a pintle 29 within the bottom section 25. This lever 28 is provided with a plurality of rack teeth 30 engageable with complementary rack teeth 31 formed on one edge of a cutout 32 formed in the top section 26. When the resilient stud 20 is passed through the opening 21' it will contact the lever 28 and pivot it towards the rack teeth 31 to engage its rack teeth 30 therewith. A spring 33 is provided for drawing the lever 28 into a position in which the teeth are disengaged, as shown in Fig. 6, when the resilient stud 20 is withdrawn from the opening 21'. A pin 34 projects from the interior of the bottom section 25 and engages a slot 35 for limiting the pivoting of the lever 28 to its operative and inoperative positions. The slot 35 is arcuately shaped and is arranged concentrically with the pin 29.

Means is provided for preventing the bottom section 25 from being completely disengaged from the bottom end of the top section 26. This means comprises pins 36 extending from the top section 26 and passing through elongated slots 37 formed in the sides of the bottom section 25. In other respects this form of the invention is similar to the previous form.

It is to be understood that this kit may be used for camping, or other purpose and be made of metal, composition or any other suitable material with a plurality of partitions. The size and proportion of the box 10 and cover 11, also of the flaps 16 may be changed as desired.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a camping kit having a box shaped body and a cover for said body and formed with a skirt wall, a flap pivotally mounted at its top end on said cover and formed with an extendable hollow bottom section formed with an opening overlying a portion of an adjacent wall of said body, a projecting stud on said adjacent wall and engageable through said opening, means in said bottom section operated by the engagement of said stud into said opening for locking said bottom section into a fixed position on said flap.

2. In a camping kit having a box shaped body and a cover for said body and formed with a skirt wall, a flap pivotally mounted at its top end

on said cover and formed with an extendable hollow bottom section formed with an opening overlying a portion of an adjacent wall of said body, a projecting stud on said adjacent wall and engageable through said opening, means in said bottom section operated by the engagement of said stud into said opening for locking said bottom section into a fixed position on said flap, comprising a lever pivotally mounted within said bottom section, teeth formed on said lever and engageable with complementary teeth formed on an adjacent portion of said flap to prevent outward movement of said bottom section on said flap, resilient means normally urging said lever to overlap a portion of said opening to be engaged by said stud when passed into said opening to move said lever to engage said teeth, and limiting means limiting the movement of said lever to a position partially overlapping said opening or to position in which said teeth are engaged.

3. In a camping kit having a box shaped body and a cover for said body and formed with a skirt wall, a flap pivotally mounted at its top end on said cover and formed with an extendable hollow bottom section formed with an opening overlying a portion of an adjacent wall of said body, a projecting stud on said adjacent wall and engageable through said opening, means in said bottom section operated by the engagement of said stud into said opening for locking said bottom section into a fixed position on said flap, comprising a lever pivotally mounted within said bottom section, teeth formed on said lever and engageable with complementary teeth formed on an adjacent portion of said flap to prevent outward movement of said bottom section on said flap, resilient means normally urging said lever to overlap a portion of said opening to be engaged by said stud when passed into said opening to move said lever to engage said teeth, and limiting means limiting the movement of said lever to a position partially overlapping said opening or to position in which said teeth are engaged, said resilient means, comprising a contraction spring operating between said lever and a fixed portion of said bottom section.

4. In a camping kit having a box shaped body and a cover for said body and formed with a skirt wall, a flap pivotally mounted at its top end on said cover and formed with an extendable hollow bottom section formed with an opening overlying a portion of an adjacent wall of said body, a projecting stud on said adjacent wall and engageable through said opening, means in said bottom section operated by the engagement of said stud into said opening for locking said bottom section into a fixed position on said flap, comprising a lever pivotally mounted within said bottom section, teeth formed on said lever and engageable with complementary teeth formed on an adjacent portion of said flap to prevent outward movement of said bottom section on said flap, resilient means normally urging said lever to overlap a portion of said opening to be engaged by said stud when passed into said opening to move said lever to engage said teeth, and limiting means limiting the movement of said lever to a position partially overlapping said opening or to position in which said teeth are engaged, said limiting means, comprising a pin from said bottom section engaging into an elongated slot formed in the free end of said lever and extended parallel to the path transversed by said free end.
